UNITED STATES PATENT OFFICE.

T. C. RICHARDS, OF MILWAUKEE, WISCONSIN.

BLOWER.

Specification of Letters Patent No. 26,863, dated January 17, 1860.

To all whom it may concern:

Be it known that I, T. C. RICHARDS, of Milwaukee, in the county of Milwaukee and State of Wisconsin, have invented a new and Improved Blower; and I do hereby declare that the following is a full, clear, and exact description of the same, reference being had to the accompanying drawings, forming part of this specification, in 10 which—

Figure 1 is a central vertical section of a blower constructed according to my invention. Fig. 2 is a horizontal section of the same.

15 Similar letters of reference indicate corresponding parts in both figures.

My improved blower consists of two or more chambers formed between an inner cylinder and an outer case by closing the 20 space between them by means of flexible material so applied as to connect the ends of the cylinder with the outer case and dividing said space lengthwise of the cylinder by partitions of flexible material, such 25 chambers, formed between said partitions, being provided with suitable inlet valves, by which they receive air from the exterior of the outer case, and with outlet valves by which they communicate with a common 30 discharge pipe. By giving the inner cylinder a movement of such character as to make it approach and recede from every part of the outer case in succession, the 35 chambers are in turn expanded and contracted and so made to collect the air from without the outer case, compress it, and deliver it into the common discharge pipe from which it is discharged in a constant stream.

40 To enable others to make and use my invention I will proceed to describe its construction and operation.

A, is the outer case which is represented of upright cylindrical form, but which may 45 be of other convenient form, made of wood or metal.

B, is the inner cylinder, which may be made of wood or metal either solid or hollow, but which in the example represented 50 is made hollow to permit the use of the particular mode represented of obtaining its necessary movement. This cylinder has its sides parallel with the vertical sides of the case A.

55 C, C, are annular pieces of leather, or other flexible material, impervious to air,

uniting the ends of the inner cylinder B, with the sides of the outer case A, so as to make the space between them perfectly air-tight, and made slack enough to permit the 60 inner cylinder to move to and from all sides of the outer case.

D, D, are upright partitions made of leather, or other flexible impervious material dividing the space between the outer 65 case and inner cylinder into several chambers E, E, said partitions being connected in such a manner as to form air-tight joints with the inner cylinder, the outer case and the flexible heads C, C, and being slack 70 enough to admit of the before mentioned movement of the inner cylinder. The inner cylinder has casters or rollers f, f, attached to its bottom to support it upon the bottom of the casing A, and enable it to move freely. 75

a, a, are inlet openings, formed in the sides of the outer casing A, for admitting air to the chambers E, E, each opening fitted with two valves b, c, opening inward. The two valves may not in all cases be necessary, 80 but one for each opening may be sufficient.

d, d, are outlet openings, formed in the sides of the outer casing A, and each connected by one of a number of short pipes F, F, with a pipe G, which encircles the 85 outer casing and from which branches off the discharge pipe or nozzle H. Each outlet opening is fitted with a valve e, opening outward.

I, is an upright shaft arranged in the center of the outer casing A, where it is fitted to suitable bearings in the top and bottom of said casing. To one side of this shaft there are attached rigidly within the cylinder B, two or more arms J, J, of equal 90 length, each carrying a roller K, to press against the interior of the cylinder B. The arms J, J, are of such length and the rollers K, K, of such diameter that the rollers bear upon one side of the cylinder while the shaft is very near the other side. The upper end of the shaft has attached to it a crank or other device by or through which to give it a rotary motion. 95

The rotary motion of the shaft I, and its 100 arms causes the rollers K, K, to roll around the interior of the cylinder and by that means to give the cylinder a circular motion around the shaft I, without any rotary motion about its own axis, such circular motion 105 being of such character that it (the cylinder B,) approaches very near to and recedes 110

from every part of the interior of the outer casing in turn, and so causes the expansion and contraction of the several chambers one after the other in regular succession. As 5 each chamber expands a partial vacuum is produced within it, and air rushes in through the valves *b*, *c*, and as the chamber is contracted or collapsed the air within it being compressed forces open the valve *e*, 10 and finds its way into the collecting pipe *G*, from whence it passes to the discharge pipe or nozzle *H*. As one or more chambers are always filling and one or more always compressing and discharging the air, a 15 steady blast from the pipe *H*, is produced.

The blower instead of being arranged vertically, as shown, may be arranged horizontally in which case each end of the cylinder *B*, may be furnished with rollers to 20 roll against the heads of the outer casing and thereby prevent any rubbing of the flexible heads *C*, *C*. Blowers constructed on this principle may be used for any of the 25

numerous purposes for which other blowers or bellows are used, and will have the advantage over the ordinary fan blower of not requiring to be driven at so high a velocity.

What I claim as my invention, and desire to secure by Letters Patent, is:—

A blower composed of an inner cylinder 30 and outer case connected by leather or other flexible substance *C*, *D*, arranged substantially as described to form two or more chambers between them, such chambers being provided each with one or more inlet 35 valves to admit air from without, and with one or more outlet valves communicating with a common discharge pipe, and the inner cylinder having a circular motion within the outer case without rotating on its own 40 axis, all substantially as herein set forth.

T. C. RICHARDS.
